UNITED STATES PATENT OFFICE.

ERIC T. JOHNSON AND GUSSIE A. LEE, OF OMAHA, NEBRASKA.

OIL-BURNER.

1,164,525.

Specification of Letters Patent. Patented Dec. 14, 1915.

Application filed March 30, 1915. Serial No. 17,966.

To all whom it may concern:

Be it known that we, ERIC T. JOHNSON and GUSSIE A. LEE, citizens of the United States, residing at Omaha, in the county of Douglas and the State of Nebraska, have invented new and useful Improvements in Oil-Burners, of which the following is a specification.

This invention relates to an improvement 10 in oil burners adapted especially for the burning of oil in stoves and furnaces.

The invention consists in the novel features of construction hereinafter described, pointed out in the claims and shown in the 15 accompanying drawings, in which:—

Figure 1 is a sectional elevation. Fig. 2 is a plan view of the lower cap. Fig. 3 is an inverted plan view of the upper cap.

In these drawings 1 designates the pan 20 having a central opening 2. Supported above the pan is a concavo-convex cap 3, spaced from the pan and supported by webs 4 carried by the under side of the cap 3. The central portion of the cap has a conical 25 depression forming a depending cone 5, into the apex portion of which is secured a supply pipe 6, a portion of which is shown. The pipe 6 discharges liquid fuel into the conical depression formed in the cap 3 by 30 the formation of the cone 5.

Fitting over the cap 3 is a larger, upper cap 7, which overhangs the cap 3. This cap is spaced from the cap 3 by lugs 8 formed on one of the caps, preferably the lower cap 3. As shown in the drawings a portion of 35 these lugs are in the central conical depression of the cone 5. The upper cap 7 has a central depending cone 9 that extends into the depression previously mentioned, being

spaced therefrom by the lugs. The over- 40 hanging portion of the cap 7 has on its underside an annular flange adjacent to but slightly spaced from the edge of the cap 3 when the caps are in position for use. The upper cap is also provided with a ring 11 45 for convenient lifting.

In operation oil or other fluid fuel is fed through the pipe 6 and is vaporized between the caps, air passing upwardly through the opening 2 and out between the webs and 50 mixing with the vapor as it passes from between the lower cap 3 and the flange 10.

A burner so constructed forms a large 55 vaporizing surface with an abundance of air therefor.

What we claim is:

1. A burner comprising a pan having an opening, a cap supported above said opening and having a hollow inverted cone, a liquid fuel pipe discharging into said cone, 60 and a second cap arranged above and spaced from the first cap and having a depending cone adapted to enter the cone of the first mentioned cap.

2. A burner comprising a pan, two superimposed caps arranged above the pan, the caps having depending cones, one within the other, the caps and cones being spaced apart, means for feeding fuel into the space 65 between the cones, and an annular flange carried by the upper cap and adjacent the edge of the lower cap, as and for the purpose set forth.

ERIC T. JOHNSON.
GUSSIE A. LEE.
